UNITED STATES PATENT OFFICE.

HARVEY L. WEST, OF ELGIN, ILLINOIS.

PIANO-ACTION.

1,167,863.

Specification of Letters Patent.

Patented Jan. 11, 1916.

Application filed January 9, 1915. Serial No. 1,285.

To all whom it may concern:

Be it known that I, HARVEY L. WEST, a citizen of the United States, and a resident of Elgin, in the county of Kane and State of Illinois, have invented certain new and useful Improvements in Piano-Actions; and I do hereby declare that the following is a full, clear, and exact description thereof, reference being had to the accompanying drawings, and to the characters of reference marked thereon, which form a part of this specification.

This invention relates to piano actions and refers more specifically to improvements in the springs by which the dampers are pressed against the strings and which yield to permit the dampers to be swung away from the springs when the keys are depressed.

Among the objects of the invention is to reduce the cost of the damper mechanism.

A further object of the invention is to produce a damper controlling spring which is connected to the damper lever in such way as to avoid squeaking noises due to the engagement of the spring with the damper lever.

Another object of the invention is to produce a novel non-shrinkable damper block which will avoid accidental detachment of the damper pad or pads from the block.

Other objects of the invention are to simplify and improve damper mechanisms, and the invention consists in the matters herein-after set forth and more particularly pointed out in the appended claims.

In the drawings:—Figure 1 is a partial sectional and partial elevation of parts of a piano action showing my invention applied thereto. Fig. 2 is an enlarged side view of the elements which constitute the damper. Fig. 3 is an enlarged front elevation thereof. Fig. 4 is a side elevation of the damper controlling springs.

The upright piano action illustrated in Fig. 1 of the drawings is of standard type and need not be specifically described except as to the parts which are immediately associated with the damper mechanism. As shown in the drawings, 10 designates one of the piano keys, 11 the abstract or lifter rod which bears at its lower end against the key and is pivotally connected to a rail 12 through the medium of a link 14. 15 designates a swinging bar or wippen which is loosely mounted on the upper end of the ab-

stract 11 and is pivotally connected at 16 to a flange or bar 17 which is carried by the action rail 18. The said wippen 15 supports the usual jack 19 which actuates the hammer 20 through engagement with the usual hammer butt 21 that is fixed to the lower end of the hammer shank 22, and the wippen also carries the back check 23 which contacts with the hammer bumper 24.

Referring now to the construction of the damper mechanism, 25 designates a damper, composed usually of a felt pad or pads attached to a damper block 26. Said damper block is of special construction, as will hereinafter be described. It is carried by the upper end of a lever 27, herein shown as made partly of wire and partly of a wood or other fibrous bar 28. The lever is pivoted at 29 to a flange or block 30 which is mounted on and secured to the action rail 18. The lower end of said damper lever is in position to be engaged by the usual spoon 31 which is attached to the wippen 15 in rear of its pivot 16; the arrangement being such that when the abstract is raised by the key 10 to bring the hammer against the string said spoon engages the damper lever to swing the damper forwardly away from the string just before it is struck by the hammer. Forward swinging movement of the damper is limited by a stop 31'.

32 designates, as a whole, a spring which acts against the damper lever to normally press the damper against its associated string. Said spring, in the form herein shown, consists of a piece of rounded wire which is anchored at its lower end to a pin 33 carried by the block or flange 30. The upper end of the spring bears against the upper end of the wood portion 28 of the damper lever. In accordance with my invention the engagement of the spring with the lever is a point engagement as distinguished from a sliding engagement. To this end, the upper end of the spring wire is bent rearwardly to constitute an engagement point 34 which enters a shallow notch or recess 35 in the forward face of the said portion 28 of the damper lever. In order to increase the resiliency of the spring at its upper end near its point of contact with said lever, and to prevent tendency of the spring to break at this point, I may form said spring at the junction of the contact point 34 and the shank of the spring with a coil 36, said coil having one or more turns,

as desired. It is to be understood, however, that, so far as the broader features of my invention are concerned, I may employ any other means for giving the desired resiliency to the spring at this point and for avoiding tendency of the spring to break under continuous flexure. The coil or other method of enhancing the resiliency of the spring has the further effect of preventing 5 the buckling of the spring in a manner tending to snap the upper end thereof out of engagement with the damper lever. The lower terminal of the spring 37 below the coil 38, by which latter it may be conveniently attached to the pin 33, is also sprung upwardly from the position shown in Fig. 4 when placed in the said block or flange so that the compression thus placed upon the spring thus forces the upper end thereof 10 rearwardly. Thus when the spring is in place it acts on the damper bar to normally hold the damper against the piano string.

Heretofore it has been a common practice to provide the upper end of the portion 28 15 of the damper lever with a padded recess to receive the upper end of the damper controlling spring. This has necessitated a special construction of the upper end of the damper lever, and has also necessitated the use of a felt or like cushioned pad in said 20 recess. The construction herein shown may, therefore, be produced at less expense than said prior construction. The prior construction is also open to the objection that the 25 sliding of the upper end of the spring on the felt or other pad causes the latter, in time, to harden to such extent that the moving contact between the pad and the spring causes an objectionable squeaking noise. In 30 the present construction the liability of such squeaking noise is entirely eliminated.

The damper block 26, herein shown, is of special construction, and has been designed with a view to avoiding shrinkage which 35 often occurs with the ordinary wood damper block and which frequently has the effect to loosen the attachment of the damper pads. The block herein shown is made principally of metal. It consists of a U-shaped piece 40 40 of strap metal, and is provided with registering openings to receive the upper end of the wire portion of the damper lever. The block may be fastened to the damper lever by means of a screw 41 which is screw- 45 threaded through the closed end of the U-shaped member and bears at its rear end against said lever. The rear ends of the

U-shaped member 40 are turned inwardly, as shown at 42, to engage opposing grooves in a member 43, preferably made of felt or 50 other soft material. To this member 43 is attached a vertically elongated head 44 to which the damper pads 25 are fixed in any suitable manner, as by means of glue. The member 43 is gripped between the ends of 55 the U-shaped member 40 by means of a screw 45 which extends through one arm of the U-shaped member and is screw-threaded to the other arm thereof.

It will be understood that the structural 70 details of the embodiment of my invention herein disclosed may be varied within the spirit and scope of the broader claims hereto attached, and that the invention is not limited to such details except as made the 75 subject of specific claims and as imposed by the prior art.

I claim as my invention:—

1. In a piano action, the combination with a damper lever and a support to which it is 80 pivoted, of a controlling spring for said lever anchored to said support and having a point pivotal engagement with the lever between the support and the damper end of the lever.

2. In a piano action, the combination with a damper lever and a support to which it is pivoted, of a spring anchored at one end to said support and entering at its other end a recess in the lever for point pivotal contact 90 with the bottom of the recess and formed to provide near its latter end a coil to increase the flexibility of the spring.

3. In a piano action, the combination with a damper head provided with a yielding 95 non-shrinkable projection, of a damper block having means to clamp it to said yielding projection to constitute a connection between the block and head.

4. In a piano action, the combination with 100 a damper head provided with a yielding non-shrinkable projection, of a U-shaped resilient damper block and clamping means acting thereon to clamp the block to said projection.

In testimony, that I claim the foregoing as my invention I affix my signature in the presence of two witnesses, this 2nd day of January, A. D. 1915.

HARVEY L. WEST.
